DESIGN FOR A BUTTON OR SIMILAR ARTICLE

William Haas, New York, N. Y.

Application December 7, 1940, Serial No. 97,162

Term of patent 3½ years

To all whom it may concern:

Be it known that I, William Haas, a citizen of the United States of America, residing in New York city, county of New York, and State of New York, have invented a new, original, and ornamental Design for a Button or Similar Article, of which the following is a specification, reference being had to the accompanying drawing, forming part thereof, wherein—

I claim:

The ornamental design for a button or similar article, substantially as shown.

WILLIAM HAAS.
